(57) **ABSTRACT**

A multilayer coil component 1 includes an element body 2, a coil 5, a first terminal electrode 3, a second terminal electrode 4, a first connection conductor 6, and a second connection conductor 7. The coil 5 includes a first coil portion 8 that has one end of the coil 5 and is disposed on a side of a main surface 2c and a second coil portion 9 that has the other end of the coil 5 and is disposed on a side of the main surface 2d. A distance L2 between the first connection conductor 6 and the second coil portion 9 is larger than a distance L1 between the first connection conductor 6 and the first coil portion 8.

TECHNICAL FIELD

The present invention relates to a multilayer coil component.

BACKGROUND

As a multilayer coil component of the related art, for example, the one described in Patent Document 1 (Japanese Unexamined Patent Publication No. 2019-16642) is known. The multilayer coil component described in Patent Document 1 includes a multilayer body in which a plurality of units are stacked. The units have a plurality of base material layers stacked and have a first main surface and a second main surface. In the units, a groove having a depth of at least one layer of the substrate layers is formed in the first main surface. In at least one unit, a hole leading to the second main surface is formed in a bottom of the groove. Each of the groove and the hole is filled with a conductor, and the plurality of units are stacked. As a result, the conductor with which the hole of one adjacent unit is filled and the conductor with which the groove of the other adjacent unit is filled are connected to each other, and inside the multilayer body, the conductors are connected to each other in a spiral shape with a stacking direction of the units as an axis.

SUMMARY

In the multilayer coil component, it is desirable to increase a diameter of a coil in order to improve characteristics. However, in a configuration in which a connection conductor is disposed inside an element body, when the diameter of the coil increases, a distance between the connection conductor and the coil decreases. As a result, stray capacitance (parasitic capacitance) formed by the coil and the connection conductor may increase. When the stray capacitance generated between the coil and the connection conductor increases, in the characteristics of the coil, a self-resonant frequency (SRF) decreases, and a quality factor (Q) value also decreases.

An object of an aspect of the present invention is to provide a multilayer coil component capable of suppressing generation of stray capacitance and improving characteristics.

A multilayer coil component according to an aspect of the present invention includes: an element body formed by stacking a plurality of insulator layers and having a pair of end surfaces facing each other, a pair of main surfaces facing each other, and a pair of side surfaces facing each other, one of the main surfaces being a mounting surface; a coil disposed in the element body and having a coil axis extending in a facing direction of the pair of main surfaces; a first terminal electrode and a second terminal electrode connected to the coil and disposed on the mounting surface; a first connection conductor disposed outside the coil in the element body when viewed in the facing direction, extending in the facing direction, and connecting one end of the coil located on a side of the other of the main surfaces and the first terminal electrode to each other; and a second connection conductor connecting the other end of the coil located on a side of the one of the main surfaces and the second terminal electrode, wherein the coil includes a first coil portion that has the one end of the coil and is disposed on a side of the other of the main surfaces and a second coil portion that has the other end of the coil and is disposed on

a side of the one of the main surfaces, and wherein a shortest distance between the first connection conductor and the second coil portion is larger than a shortest distance between the first connection conductor and the first coil portion.

In the multilayer coil component, a potential difference between the first terminal electrode and the second terminal electrode reaches a maximum. When conductors with a large potential difference face each other, stray capacitance is formed. In the multilayer coil component, the first connection conductor connected to the first terminal electrode extends in the facing direction. In this configuration, stray capacitance is formed between the first connection conductor and the coil due to a potential difference between the first connection conductor and the coil. In particular, stray capacitance is likely to be formed between the coil connected to a side of the second terminal electrode and the first connection conductor. Incidentally, in the multilayer coil component, the shortest distance between the first connection conductor and the second coil portion is larger than the shortest distance between the first connection conductor and the first coil portion. As a result, in the multilayer coil component, the second coil portion with a large potential difference from the first connection conductor is disposed farther from the first connection conductor than the first coil portion. Therefore, in the multilayer coil component, stray capacitance formed between the first connection conductor and the second coil portion can be reduced. Further, in the multilayer coil component, the diameter of the first coil portion can be increased. Therefore, the inductance of the coil can be increased. As described above, in the multilayer coil component, it is possible to suppress the generation of stray capacitance and to increase the characteristics.

In the embodiment, a diameter of the first coil portion and a diameter of the second coil portion may be different, and a part of an outer edge of the first coil portion and a part of an outer edge of the second coil portion may overlap each other when viewed in the facing direction. In this configuration, since a part of an outer edge of the first coil portion and a part of an outer edge of the second coil portion overlap each other, the diameter of the second coil portion can be increased while ensuring the distance between the first connection conductor and the second coil portion.

In the embodiment, the first terminal electrode and the second coil portion may not overlap each other when viewed in the facing direction. In this configuration, it is possible to suppress the formation of stray capacitance between the first terminal electrode and the second coil portion.

In the embodiment, a distance between the first connection conductor and the coil may be set on the basis of a potential difference between the first connection conductor and the coil during use, and the distance may be longer at a position where the potential difference is large than at a position where the potential difference is smaller than at the position where the potential difference is large. In this configuration, since the distance is set according to the potential difference, the stray capacitance can be reduced.

According to the aspect of the present invention, it is possible to suppress generation of stray capacitance and improve characteristics.

BRIEF DESCRIPTION OF THE DRAWINGS

FIG. 1 is a perspective view of a multilayer coil component according to a first embodiment.

FIG. 2 is a side view of the multilayer coil component shown in FIG. 1.

FIG. 3 is an exploded perspective view of the multilayer coil component shown in FIG. 1.

FIG. 4 is a perspective view of a multilayer coil component according to a second embodiment.

FIG. 5 is a side view of the multilayer coil component shown in FIG. 4.

FIG. 6 is an exploded perspective view of the multilayer coil component shown in FIG. 4.

FIG. 7 is a perspective view of a multilayer coil component according to a third embodiment.

FIG. 8 is a side view of the multilayer coil component shown in FIG. 7.

FIG. 9 is an exploded perspective view of the multilayer coil component shown in FIG. 7.

FIG. 10 is a top view of the multilayer coil component shown in FIG. 7.

FIG. 11 is a perspective view of a multilayer coil component according to a fourth embodiment.

FIG. 12 is a side view of the multilayer coil component shown in FIG. 11.

FIG. 13 is an exploded perspective view of the multilayer coil component shown in FIG. 11.

FIG. 14 is a perspective view of a multilayer coil component according to a fifth embodiment.

FIG. 15 is a side view of the multilayer coil component shown in FIG. 14.

FIG. 16 is an exploded perspective view of the multilayer coil component shown in FIG. 14.

DETAILED DESCRIPTION

Hereinafter, preferred embodiments of the present invention will be described in detail with reference to the accompanying drawings. In the description of the drawings, the same or equivalent elements are designated by the same reference signs, and duplicate description will be omitted.

First Embodiment

A multilayer coil component according to a first embodiment will be described with reference to FIGS. 1 and 2. FIG. 1 is a perspective view of the multilayer coil component according to the first embodiment. FIG. 2 is a side view of the multilayer coil component shown in FIG. 1. As shown in FIGS. 1 and 2, a multilayer coil component 1 according to the first embodiment includes an element body 2, a first terminal electrode 3, a second terminal electrode 4, a coil 5, a first connection conductor 6, and a second connection conductor 7. In FIGS. 1 and 2, the element body 2 is shown by a broken line for convenience of explanation.

The element body 2 has a rectangular parallelepiped shape. The rectangular parallelepiped shape may be a shape of a rectangular parallelepiped in which corners and ridges are chamfered or a shape of a rectangular parallelepiped in which corners and ridges are rounded. The element body 2 has a pair of end surfaces 2a and 2b, a pair of main surfaces 2c and 2d, and a pair of side surfaces 2e and 2f as outer surfaces. The end surfaces 2a and 2b face each other. The main surfaces 2c and 2d face each other. The side surfaces 2e and 2f face each other. In the following, a facing direction of the main surfaces 2c and 2d is referred to as a first direction D1, a facing direction of the end surfaces 2a and 2b is referred to as a second direction D2, and a facing direction of the side surfaces 2e and 2f is referred to as a third direction D3. The first direction D1, the second direction D2, and the third direction D3 are substantially orthogonal to each other.

The end surfaces 2a and 2b extend in the first direction D1 to connect the main surfaces 2c and 2d to each other. The end surfaces 2a and 2b also extend in the third direction D3 to connect the side surfaces 2e and 2f to each other. The main surfaces 2c and 2d extend in the second direction D2 to connect the end surfaces 2a and 2b to each other. The main surfaces 2c and 2d also extend in the third direction D3 to connect the side surfaces 2e and 2f to each other. The side surfaces 2e and 2f extend in the first direction D1 to connect the main surfaces 2c and 2d to each other. The side surfaces 2e and 2f also extend in the second direction D2 to connect the end surfaces 2a and 2b to each other.

The main surface 2d (one of the main surfaces) is a mounting surface, for example, a surface which faces another electronic device (for example, a circuit base material or a multilayer electronic component), which is not shown, when the multilayer coil component 1 is mounted on the other electronic device. The end surfaces 2a and 2b are surfaces continuous from the mounting surface (that is, the main surface 2d).

The length of the element body 2 in the second direction D2 is longer than each of the length of the element body 2 in the first direction D1 and the length of the element body 2 in the third direction D3. The length of the element body 2 in the first direction D1 is longer than the length of the element body 2 in the third direction D3. That is, in the present embodiment, the end surfaces 2a and 2b, the main surfaces 2c and 2d, and the side surfaces 2e and 2f form a rectangular shape. The length of the element body 2 in the second direction D2 may be equivalent to each of the length of the element body 2 in the first direction D1 and the length of the element body 2 in the third direction D3, or may be shorter than each of these lengths.

In addition, in the present embodiment, "equivalent" may indicate a value including a slight difference or a manufacturing error in a preset range in addition to being equal. For example, under this definition, if a plurality of values are included within the range of $\pm 5\%$ of the average value of the plurality of values, the plurality of values are equivalent.

The element body 2 is formed by stacking a plurality of element body layers (insulator layers) 10a to 10k (see FIG. 3) in the first direction D1. That is, a stacking direction of the element body 2 is the first direction D1. A specific stacking configuration will be described later. In the actual element body 2, the plurality of element body layers 10a to 10k are integrated to the extent that a boundary between the layers cannot be visually recognized. The element body layers 10a to 10k are made of, for example, a magnetic material (a Ni—Cu—Zn based ferrite material, a Ni—Cu—Zn—Mg based ferrite material, a Ni—Cu based ferrite material, or the like). The magnetic material forming the element body layers 10a to 10k may contain an Fe alloy or the like. The element body layers 10a to 10k may be made of a nonmagnetic material (a glass ceramic material, a dielectric material, or the like).

Each of the first terminal electrode 3 and the second terminal electrode 4 is provided on the element body 2. The first terminal electrode 3 is constituted by a first terminal electrode layer 18k (see FIG. 3). The second terminal electrode 4 is constituted by a second terminal electrode layer 19k (see FIG. 3). Each of the first terminal electrode 3 and the second terminal electrode 4 is disposed on the main surface 2d of the element body 2. The first terminal electrode 3 and the second terminal electrode 4 are provided on the element body 2 apart from each other in the second direction D2. Specifically, the first terminal electrode 3 is disposed on a side of the end surface 2a of the element body 2. The

second terminal electrode 4 is disposed on a side of the end surface 2b of the element body 2.

Each of the first terminal electrode 3 and the second terminal electrode 4 has a rectangular shape (a rectangular shape). Each of the first terminal electrode 3 and the second terminal electrode 4 is disposed such that a longitudinal direction thereof is the third direction D3 and a lateral direction thereof is the second direction D2. As shown in FIG. 2, the first terminal electrode 3 and the second terminal electrode 4 protrude from the main surface 2d. That is, in the present embodiment, a surface of each of the first terminal electrode 3 and the second terminal electrode 4 is not flush with the main surface 2d.

Each of the first terminal electrode 3 and the second terminal electrode 4 may be provided with a plated layer (not shown) containing, for example, Ni, Sn, Au, or the like by being subjected to electroplating or electroless plating. The plated layer may have, for example, a Ni plated film containing Ni and covering the first terminal electrode 3 and the second terminal electrode 4 and a Au plated film containing Au and covering the Ni plated film.

The coil 5 is disposed in the element body 2. The coil 5 is constituted by a plurality of coil conductor layers 12b to 12h (see FIG. 3). The plurality of coil conductor layers 12b to 12h are connected to each other to constitute the coil 5 in the element body 2. A coil axis of the coil 5 is provided in the first direction D1. The coil conductor layers 12b to 12h are disposed such that at least parts thereof overlap each other when viewed in the first direction D1. The plurality of coil conductor layers 12b to 12h are made of a conductive material (for example, Ag or Pd). The coil conductor layers 12b to 12h are disposed apart from the end surfaces 2a and 2b, the main surfaces 2c and 2d, and the side surfaces 2e and 2f.

The coil 5 includes a first coil portion 8 and a second coil portion 9. The first coil portion 8 is constituted by the plurality of coil conductor layers 12b to 12d. The first coil portion 8 is disposed on a side of the main surface 2c of the element body 2. The first coil portion 8 has one end of the coil 5 connected to the first connection conductor 6. The first coil portion 8 is connected to the first connection conductor 6. The second coil portion 9 is constituted by the plurality of coil conductor layers 12e to 12h. The second coil portion 9 is disposed on a side of the main surface 2d of the element body 2. The second coil portion 9 has the other end of the coil 5 connected to the second connection conductor 7. The second coil portion 9 is connected to the second connection conductor 7.

The first connection conductor 6 is disposed in the element body 2. The first connection conductor 6 connects the first terminal electrode 3 and the coil 5 to each other. The first connection conductor 6 is a through hole conductor. The first connection conductor 6 extends in the first direction D1 and is connected to the first terminal electrode 3 and the one end of the coil 5. Specifically, an end portion of the first connection conductor 6 on a side of the main surface 2c (the other of the main surfaces) in the first direction D1 is connected to the one end of the coil 5 located on a side of the main surface 2c. The first connection conductor 6 is constituted by a plurality of first connection conductor layers 14c to 14j (see FIG. 3). The first connection conductor 6 is disposed outside the coil 5 when viewed in the first direction D1. Specifically, the first connection conductor 6 is disposed at a corner when viewed in the first direction D1. More specifically, the first connection conductor 6 is disposed at a corner formed by the end surface 2a and the side surface 2e. In the first connection conductor 6, a cross section orthogo-

nal to an extending direction (the first direction D1) (a cross section in the second direction D2 and the third direction D3) has a round shape. That is, the first connection conductor 6 has the shape of a circular column. Round shapes include, for example, a perfect circle, an ellipse, and the like.

The second connection conductor 7 is disposed in the element body 2. The second connection conductor 7 connects the second terminal electrode 4 and the coil 5 to each other. The second connection conductor 7 is a through hole conductor. The second connection conductor 7 extends in the first direction D1 and is connected to the second terminal electrode 4 and the other end of the coil 5. Specifically, an end portion of the second connection conductor 7 on a side of the main surface 2c in the first direction D1 is connected to the other end of the coil 5 located on a side of the main surface 2d. The second connection conductor 7 is constituted by a plurality of second connection conductor layers 16i and 16j (see FIG. 3). The second connection conductor 7 is disposed at a corner when viewed in the first direction D1. More specifically, the second connection conductor 7 is disposed at a corner formed by the end surface 2b and the side surface 2f. That is, the second connection conductor 7 is disposed diagonally with the first connection conductor 6.

FIG. 3 is an exploded perspective view of the multilayer coil component shown in FIG. 1. As shown in FIG. 3, the multilayer coil component 1 includes a plurality of layers La, Lb, Lc, Ld, Le, Lf, Lg, Lh, Li, Lj, and Lk. The multilayer coil component 1 is constituted by the layers La to Lk being stacked in order from a side of the main surface 2c, for example.

The layer La is constituted by the element body layer 10a.

The layer Lb is formed by combining the element body layer 10b and the coil conductor layer 12b with each other. The element body layer 10b is provided with a defective portion Rb which has a shape corresponding to the coil conductor layer 12b and into which the coil conductor layer 12b is fitted. The element body layer 10b and the coil conductor layer 12b have a complementary relationship with each other.

The layer Lc is formed by combining the element body layer 10c, the coil conductor layer 12c, and the first connection conductor layer 14c with each other. The element body layer 10c is provided with a defective portion Rc which has a shape corresponding to the coil conductor layer 12c and the first connection conductor layer 14c and into which the coil conductor layer 12c and the first connection conductor layer 14c are fitted. The element body layer 10c and the entirety of the coil conductor layer 12c and the first connection conductor layer 14c have a complementary relationship with each other.

The layer Ld is formed by combining the element body layer 10d, the coil conductor layer 12d, and the first connection conductor layer 14d with each other. The element body layer 10d is provided with a defective portion Rd which has a shape corresponding to the coil conductor layer 12d and the first connection conductor layer 14d and into which the coil conductor layer 12d and the first connection conductor layer 14d are fitted. The element body layer 10d and the entirety of the coil conductor layer 12d and the first connection conductor layer 14d have a complementary relationship with each other.

The layer L_e is formed by combining the element body layer $10e$, the coil conductor layer $12e$, and the first connection conductor layer $14e$ with each other. The element body layer $10e$ is provided with a defective portion R_e which has a shape corresponding to the coil conductor layer $12e$ and the first connection conductor layer $14e$ and into which the coil conductor layer $12e$ and the first connection conductor layer $14e$ are fitted. The element body layer $10e$ and the entirety of the coil conductor layer $12e$ and the first connection conductor layer $14e$ have a complementary relationship with each other.

The layer L_f is formed by combining the element body layer $10f$, the coil conductor layer $12f$, and the first connection conductor layer $14f$ with each other. The element body layer $10f$ is provided with a defective portion R_f which has a shape corresponding to the coil conductor layer $12f$ and the first connection conductor layer $14f$ and into which the coil conductor layer $12f$ and the first connection conductor layer $14f$ are fitted. The element body layer $10f$ and the entirety of the coil conductor layer $12f$ and the first connection conductor layer $14f$ have a complementary relationship with each other.

The layer L_g is formed by combining the element body layer $10g$, the coil conductor layer $12g$, and the first connection conductor layer $14g$ with each other. The element body layer $10g$ is provided with a defective portion R_g which has a shape corresponding to the coil conductor layer $12g$ and the first connection conductor layer $14g$ and into which the coil conductor layer $12g$ and the first connection conductor layer $14g$ are fitted. The element body layer $10g$ and the entirety of the coil conductor layer $12g$ and the first connection conductor layer $14g$ have a complementary relationship with each other.

The layer L_h is formed by combining the element body layer $10h$, the coil conductor layer $12h$, and the first connection conductor layer $14h$ with each other. The element body layer $10h$ is provided with a defective portion R_h which has a shape corresponding to the coil conductor layer $12h$ and the first connection conductor layer $14h$ and into which the coil conductor layer $12h$ and the first connection conductor layer $14h$ are fitted. The element body layer $10h$ and the entirety of the coil conductor layer $12h$ and the first connection conductor layer $14h$ have a complementary relationship with each other.

The layer L_i is formed by combining the element body layer $10i$, the first connection conductor layer $14i$, and the second connection conductor layer $16i$ with each other. The element body layer $10i$ is provided with a defective portion R_i which has a shape corresponding to the first connection conductor layer $14i$ and the second connection conductor layer $16i$ and into which the first connection conductor layer $14i$ and the second connection conductor layer $16i$ are fitted. The element body layer $10i$ and the entirety of the first connection conductor layer $14i$ and the second connection conductor layer $16i$ have a complementary relationship with each other.

The layer L_j is formed by combining the element body layer $10j$, the first connection conductor layer $14j$, and the second connection conductor layer $16j$ with each other. The element body layer $10j$ is provided with a defective portion R_j which has a shape corresponding to the first connection conductor layer $14j$ and the second connection conductor layer $16j$ and into which the first connection conductor layer $14j$ and the second connection conductor layer $16j$ are fitted. The element body layer $10j$ and the entirety of the first

connection conductor layer $14j$ and the second connection conductor layer $16j$ have a complementary relationship with each other.

The layer L_k is formed by combining the element body layer $10k$, the first terminal electrode layer $18k$, and the second terminal electrode layer $19k$ with each other. The element body layer $10k$ is provided with a defective portion R_k which has a shape corresponding to the first terminal electrode layer $18k$ and the second terminal electrode layer $19k$ and into which the first terminal electrode layer $18k$ and the second terminal electrode layer $19k$ are fitted. The element body layer $10k$ and the entirety of the first terminal electrode layer $18k$ and the second terminal electrode layer $19k$ have a complementary relationship with each other.

The width of each of the defective portions R_b to R_k (hereinafter referred to as the width of the defective portion) is basically set to be wider than the width of each of the coil conductor layers $12b$ to $12h$, the first connection conductor layers $14c$ to $14j$, the second connection conductor layers $16i$ and $16j$, and the first and second terminal electrode layers $18k$ and $19k$ (hereinafter referred to as the width of a conductor portion). In order to improve adhesion between the element body layers $10b$ to $10k$ and the coil conductor layers $12b$ to $12h$, the first connection conductor layers $14c$ to $14j$, the second connection conductor layers $16i$ and $16j$, and the first and second terminal electrode layers $18k$ and $19k$, the width of the defective portion may be intentionally set to be narrower than the width of the conductor portion. A value obtained by subtracting the width of the conductor portion from the width of the defective portion is preferably $-3 \mu\text{m}$ or more and $10 \mu\text{m}$ or less and more preferably $0 \mu\text{m}$ or more and $10 \mu\text{m}$ or less, for example.

As shown in FIG. 2, in the multilayer coil component 1 , a distance L_2 between the first connection conductor 6 and the second coil portion 9 is larger than a distance L_1 between the first connection conductor 6 and the first coil portion 8 ($L_2 > L_1$). In other words, the distance L_1 between the first connection conductor 6 and the first coil portion 8 is smaller than the distance L_2 between the first connection conductor 6 and the second coil portion 9 ($L_1 < L_2$). That is, the second coil portion 9 is disposed farther from the first connection conductor 6 than the first coil portion 8 . The distance L_1 is the shortest distance between the first connection conductor 6 and the first coil portion 8 (the coil conductor layers $12b$ to $12d$). The distance L_2 is the shortest distance between the first connection conductor 6 and the second coil portion 9 (the coil conductor layers $12e$ to $12h$). In FIG. 2, the distance L_1 and the distance L_2 are shown as an example for convenience and may differ from the actual shortest distance.

A diameter of the first coil portion 8 and a diameter of the second coil portion 9 are different. The diameter of the first coil portion 8 is larger than the diameter of the second coil portion 9 . In other words, the diameter of the second coil portion 9 is smaller than the diameter of the first coil portion 8 . A coil axis of the first coil portion 8 and a coil axis of the second coil portion 9 do not coincide with each other. The coil axis of the second coil portion 9 is located closer to the end surface $2b$ than the coil axis of the first coil portion 8 . An edge of the first coil portion 8 and an edge of the second coil portion 9 on a side of the end surface $2b$ of the element body 2 coincide with each other in the first direction D_1 . Specifically, when viewed in the first direction D_1 , a part of the coil conductor layer $12b$ constituting the first coil portion 8 and parts of the coil conductor layer $12e$ and the coil conductor layer $12h$ constituting the second coil portion 9 overlap each other.

The second coil portion **9** does not overlap the first terminal electrode **3** when viewed in the first direction D1. That is, the second coil portion **9** is not located above the first terminal electrode **3**. Specifically, the coil conductor layers **12e** to **12h** do not overlap the first terminal electrode **3** when viewed in the first direction D1.

An example of a manufacturing method of the multilayer coil component **1** according to the embodiment will be described.

First, an element body forming layer is formed by applying an element body paste containing the above-mentioned constituent material of the element body layers **10a** to **10k** and a photosensitive material onto a base material (for example, a PET film). The photosensitive material contained in the element body paste may be either a negative type or a positive type, and a known material can be used as the photosensitive material. Subsequently, for example, the element body forming layer is exposed and developed by a photolithography method using a Cr mask, and thus an element body pattern from which a shape corresponding to a shape of a conductor forming layer, which will be described later, is removed is formed on the base material. The element body pattern is a layer to be each of the element body layers **10a** to **10k** after heat treatment. That is, the element body pattern in which a defective portion to be each of the defect portions Rb to Rk is provided is formed. The "photolithography method" of the present embodiment only have to be any one in which a layer containing the photosensitive material to be processed is processed into a desired pattern by being exposed and developed and is not limited to the type of mask or the like.

On the other hand, a conductor forming layer is formed by applying a conductor paste containing the above-mentioned constituent material of the coil conductor layers **12b** to **12h**, the first connection conductor layers **14c** to **14j**, the second connection conductor layers **16i** and **16j**, and the first and second terminal electrode layers **18k** and **19k** and a photosensitive material onto a base material (for example, a PET film). The photosensitive material contained in the conductor paste may be either a negative type or a positive type, and a known material can be used as the photosensitive material. Subsequently, for example, the conductor forming layer is exposed and developed by a photolithography method using a Cr mask, and thus a conductor pattern is formed on the base material. The conductor pattern is a layer to be each of the coil conductor layers **12b** to **12h**, the first connection conductor layers **14c** to **14j**, the second connection conductor layers **16i** and **16j**, and the first and the second terminal electrode layers **18k** and **19k** after heat treatment.

Subsequently, the element body forming layer is transferred from the base material onto a support. The element body forming layer is a layer to be the layer La after heat treatment.

Subsequently, the conductor pattern and the element body pattern are repeatedly transferred onto a support, and thus the conductor pattern and the element body pattern are stacked in the third direction D3. Specifically, first, the conductor pattern is transferred from the base material onto the element body forming layer. Next, the element body pattern is transferred from the base material onto the element body forming layer. The conductor pattern is combined with the defective portion of the element body pattern, and the element body pattern and the conductor pattern become the same layer on the element body forming layer. Further, a transfer step of the conductor pattern and the element body pattern is repeatedly carried out, and thus the conductor pattern and the element body pattern are stacked in a state of

being combined with each other. As a result, layers to be the layers Lb to Lk after heat treatment are stacked.

Subsequently, the element body forming layer is transferred from the base material onto the layers stacked in the transfer step of the conductor pattern and the element body pattern. The element body forming layer is a layer to be the layer La after heat treatment.

As described above, a multilayer body that constitutes the multilayer coil component **1** after heat treatment is formed on the support. Subsequently, the obtained multilayer body is cut into a predetermined size. After that, the cut multilayer body is subjected to binder removal treatment and then heat treatment. A heat treatment temperature is, for example, about 850°C. to 900°C. If necessary, after heat treatment, the first terminal electrode **3** and the second terminal electrode **4** may be provided with a plated layer by being subjected to electroplating or electroless plating.

In the multilayer coil component **1**, a potential difference between the first terminal electrode **3** and the second terminal electrode **4** reaches a maximum. When conductors with a large potential difference face each other, stray capacitance is formed. In the multilayer coil component **1**, the first connection conductor **6** connected to the first terminal electrode **3** extends in the first direction D1. In this configuration, stray capacitance is formed between the first connection conductor **6** and the coil **5** due to a potential difference between the first connection conductor **6** and the coil **5**. In particular, stray capacitance is likely to be formed between the coil **5** connected to a side of the second terminal electrode **4** and the first connection conductor **6**. Incidentally, in the multilayer coil component **1**, the distance L2 between the first connection conductor **6** and the second coil portion **9** is larger than the distance L1 between the first connection conductor **6** and the first coil portion **8**. As a result, in the multilayer coil component **1**, the second coil portion **9** with a large potential difference from the first connection conductor **6** is disposed farther from the first connection conductor **6** than the first coil portion **8**. Therefore, in the multilayer coil component **1**, stray capacitance formed between the first connection conductor **6** and the second coil portion **9** can be reduced. Further, in the multilayer coil component **1**, the diameter of the first coil portion **8** can be increased. Therefore, the inductance of the coil **5** can be increased. As described above, in the multilayer coil component **1**, it is possible to suppress the generation of stray capacitance and to increase the characteristics.

In the multilayer coil component **1** of the present embodiment, an outer edge of the first coil portion **8** and an outer edge of the second coil portion **9** on a side of the end surface 2b of the element body **2** coincide with each other in the first direction D1. In this configuration, the diameter of the second coil portion **9** can be increased while ensuring the distance between the first connection conductor **6** and the second coil portion **9**.

In the multilayer coil component **1** according to the present embodiment, the first terminal electrode **3** and the second coil portion **9** do not overlap each other when viewed in the first direction D1. In this configuration, it is possible to suppress the formation of stray capacitance between the first terminal electrode **3** and the second coil portion **9**.

Second Embodiment

Subsequently, a multilayer coil component according to a second embodiment will be described with reference to FIGS. 4 and 5. FIG. 4 is a perspective view of the multilayer coil component according to the second embodiment. FIG.

11

5 is a side view of the multilayer coil component shown in FIG. 4. As shown in FIGS. 4 and 5, a multilayer coil component 1A according to the second embodiment includes an element body 2, a first terminal electrode 3, a second terminal electrode 4, a coil 5A, a first connection conductor 6, and a second connection conductor 7. In FIGS. 4 and 5, the element body 2 is shown by a broken line for convenience of explanation.

The element body 2 is formed by stacking a plurality of element body layers 20a to 20k (see FIG. 6) in the first direction D1.

The coil 5A is disposed in the element body 2. The coil 5A is constituted by a plurality of coil conductor layers 22b to 22h (see FIG. 6). The plurality of coil conductor layers 22b to 22h are connected to each other to constitute the coil 5A in the element body 2. A coil axis of the coil 5A is provided in the first direction D1. The coil conductor layers 22b to 22h are disposed such that at least parts thereof overlap each other when viewed in the first direction D1. The plurality of coil conductor layers 22b to 22h are made of a conductive material (for example, Ag or Pd). The coil conductor layers 22b to 22h are disposed apart from the end surfaces 2a and 2b, the main surfaces 2c and 2d, and the side surfaces 2e and 2f.

The coil 5A includes a first coil portion 8A and a second coil portion 9A. The first coil portion 8A is constituted by the plurality of coil conductor layers 22b to 22d. The first coil portion 8A is disposed on a side of the main surface 2c of the element body 2. The first coil portion 8A has one end of the coil 5A connected to the first connection conductor 6. The first coil portion 8A is connected to the first connection conductor 6. The second coil portion 9A is constituted by the plurality of coil conductor layers 22e to 22h. The second coil portion 9A is disposed on a side of the main surface 2d of the element body 2. The second coil portion 9A has the other end of the coil 5A connected to the second connection conductor 7. The second coil portion 9A is connected to the second connection conductor 7.

FIG. 6 is an exploded perspective view of the multilayer coil component. As shown in FIG. 6, the multilayer coil component 1A includes a plurality of layers LAa, LAB, LAC, LAd, LAe, LAg, LAf, LAh, LAi, LAj, and LAK. The multilayer coil component 1A is constituted by the layers LAa to LAK being stacked in order from a side of the main surface 2c, for example.

The layer LAa is constituted by the element body layer 20a.

The layer LAB is formed by combining the element body layer 20b and the coil conductor layer 22b with each other. The element body layer 20b is provided with a defective portion RAb. The layer LAC is formed by combining the element body layer 20c, the coil conductor layer 22c, and a first connection conductor layer 24c with each other. The element body layer 20c is provided with a defective portion RAc.

The layer LAd is formed by combining the element body layer 20d, the coil conductor layer 22d, and a first connection conductor layer 24d with each other. The element body layer 20d is provided with a defective portion RAd. The layer LAe is formed by combining the element body layer 20e, the coil conductor layer 22e, and a first connection conductor layer 24e with each other. The element body layer 20e is provided with a defective portion RAe.

The layer LAg is formed by combining the element body layer 20f, the coil conductor layer 22f, and a first connection conductor layer 24f with each other. The element body layer 20f is provided with a defective portion RAf. The layer LAf

12

is formed by combining the element body layer 20g, the coil conductor layer 22g, and a first connection conductor layer 24g with each other. The element body layer 20g is provided with a defective portion RAg.

5 The layer LAh is formed by combining the element body layer 20h, the coil conductor layer 22h, and a first connection conductor layer 24h with each other. The element body layer 20h is provided with a defective portion RAh. The layer LAi is formed by combining the element body layer 20i, a first connection conductor layer 24i, and a second connection conductor layer 26i with each other. The element body layer 20i is provided with a defective portion RAi.

The layer LAj is formed by combining the element body layer 20j, a first connection conductor layer 24j, and a second connection conductor layer 26j with each other. The element body layer 20j is provided with a defective portion RAj. The layer LAK is formed by combining the element body layer 20k, a first terminal electrode layer 28k, and a second terminal electrode layer 29k with each other. The element body layer 20k is provided with a defective portion RAK.

10 As shown in FIG. 5, in the multilayer coil component 1A, a distance L2 between the first connection conductor 6 and the second coil portion 9A is larger than a distance L1 between the first connection conductor 6 and the first coil portion 8A. In other words, the distance L1 between the first connection conductor 6 and the first coil portion 8A is smaller than the distance L2 between the first connection conductor 6 and the second coil portion 9A. That is, the second coil portion 9A is disposed farther from the first connection conductor 6 than the first coil portion 8A. The distance L1 is the shortest distance between the first connection conductor 6 and the first coil portion 8A (the coil conductor layers 22b to 22d). The distance L2 is the shortest distance between the first connection conductor 6 and the second coil portion 9A (the coil conductor layers 22e to 22h). In FIG. 5, the distance L1 and the distance L2 are shown as an example for convenience and may differ from the actual shortest distance.

15 In the first coil portion 8A, a distance between the first connection conductor 6 and the coil conductor layer 22d is than a distance between the first connection conductor 6 and the coil conductor layer 22c. That is, in a path of the first terminal electrode 3, the first connection conductor 6, the coil 5A, the second connection conductor 7, and the second

20 terminal electrode 4, the coil conductor layer 22d closer to the second terminal electrode 4 is disposed farther from the first connection conductor 6 than the coil conductor layer 22c. In the second coil portion 9A, a distance between the first connection conductor 6 and the coil conductor layer 22g is larger than a distance between the first connection conductor 6 and the coil conductor layer 22f. That is, in the above path, the coil conductor layer 22g closer to the second terminal electrode 4 is disposed farther from the first connection conductor 6 than the coil conductor layer 22f.

25 In the multilayer coil component 1A, the distances between the first connection conductor 6 and the coil conductor layers 22c and 22d of the first coil portion 8A are set on the basis of a potential difference generated when the multilayer coil component 1A is used. Specifically, in the multilayer coil component 1A, the distances between the first connection conductor 6 and the coil conductor layers 22c and 22d are set such that the larger a potential difference between the coil conductor layer and the first connection conductor 6, the larger a distance between the coil conductor layer and the first connection conductor 6. A potential difference between the first connection conductor 6 and the

coil conductor layer 22d is larger than a potential difference between the first connection conductor 6 and the coil conductor layer 22c. As a result, in the multilayer coil component 1A, in the first coil portion 8A, the distance between the first connection conductor 6 and the coil conductor layer becomes larger in the order of the distance between the first connection conductor 6 and the coil conductor layer 22c and the distance between the first connection conductor 6 and the coil conductor layer 22d. Similarly, in the multilayer coil component 1A, in the second coil portion 9A, the distance between the first connection conductor 6 and the coil conductor layer becomes larger in the order of the distance between the first connection conductor 6 and the coil conductor layer 22f and the distance between the first connection conductor 6 and the coil conductor layer 22g.

A diameter of the first coil portion 8A and a diameter of the second coil portion 9A are different. The diameter of the first coil portion 8A is larger than the diameter of the second coil portion 9A. In other words, the diameter of the second coil portion 9A is smaller than the diameter of the first coil portion 8A. A coil axis of the first coil portion 8A and a coil axis of the second coil portion 9A do not coincide with each other. The coil axis of the second coil portion 9A is located closer to the end surface 2b than the coil axis of the first coil portion 8A. An edge of the first coil portion 8A and an edge of the second coil portion 9A on a side of the end surface 2b of the element body 2 coincide with each other in the first direction D1. Specifically, when viewed in the first direction D1, a part of the coil conductor layer 22b constituting the first coil portion 8A and parts of the coil conductor layer 22e and the coil conductor layer 22h constituting the second coil portion 9A overlap each other.

The second coil portion 9A does not overlap the first terminal electrode 3 when viewed in the first direction D1. That is, the second coil portion 9A is not located above the first terminal electrode 3. Specifically, the coil conductor layers 22e to 22h do not overlap the first terminal electrode 3 when viewed in the first direction D1.

As described above, in the multilayer coil component 1A according to the present embodiment, similarly to the multilayer coil component 1, the distance L2 between the first connection conductor 6 and the second coil portion 9A is larger than the distance L1 between the first connection conductor 6 and the first coil portion 8A. As a result, in the multilayer coil component 1A, the second coil portion 9A with a large potential difference from the first connection conductor 6 is disposed farther from the first connection conductor 6 than the first coil portion 8A. Therefore, in the multilayer coil component 1A, stray capacitance formed between the first connection conductor 6 and the second coil portion 9A can be reduced. Further, in the multilayer coil component 1A, the diameter of the first coil portion 8A can be increased. Therefore, the inductance of the coil 5A can be increased. As described above, in the multilayer coil component 1A, it is possible to suppress the generation of stray capacitance and to increase the characteristics.

In the multilayer coil component 1A according to the present embodiment, the distances between the first connection conductor 6 and the coil conductor layers 22c and 22d of the first coil portion 8A and the distances between the first connection conductor 6 and the coil conductor layers 22f and 22g of the second coil portion 9A are set on the basis of a potential difference generated when the multilayer coil component 1A is used. The potential difference between the first connection conductor 6 and the coil conductor layer 22d is larger than the potential difference between the first connection conductor 6 and the coil conductor layer 22c. Therefore,

in the first coil portion 8A, the distance between the first connection conductor 6 and the coil conductor layer 22d is larger than the distance between the first connection conductor 6 and the coil conductor layer 22c. Further, the potential difference between the first connection conductor 6 and the coil conductor layer 22g is larger than the potential difference between the first connection conductor 6 and the coil conductor layer 22h. Therefore, in the second coil portion 9A, the distance between the first connection conductor 6 and the coil conductor layer 22g is larger than the distance between the first connection conductor 6 and the coil conductor layer 22f. In this configuration, since the distance is set according to the potential difference, the stray capacitance can be reduced.

Third Embodiment

Subsequently, a multilayer coil component according to a third embodiment will be described with reference to FIGS. 7 and 8. FIG. 7 is a perspective view of the multilayer coil component according to the third embodiment. FIG. 8 is a side view of the multilayer coil component shown in FIG. 7. As shown in FIGS. 7 and 8, a multilayer coil component 1B according to the third embodiment includes an element body 2, a first terminal electrode 3, a second terminal electrode 4, a coil 5B, a first connection conductor 6, and a second connection conductor 7. In FIGS. 7 and 8, the element body 2 is shown by a broken line for convenience of explanation.

The element body 2 is formed by stacking a plurality of element body layers 30a to 30k (see FIG. 9) in the first direction D1.

The coil 5B is disposed in the element body 2. The coil 5B is constituted by a plurality of coil conductor layers 32b to 32h (see FIG. 9). The plurality of coil conductor layers 32b to 32h are connected to each other to constitute the coil 5B in the element body 2. A coil axis of the coil 5B is provided in the first direction D1. The coil conductor layers 32b to 32h are disposed such that at least parts thereof overlap each other when viewed in the first direction D1. The plurality of coil conductor layers 32b to 32h are made of a conductive material (for example, Ag or Pd). The coil conductor layers 32b to 32h are disposed apart from the end surfaces 2a and 2b, the main surfaces 2c and 2d, and the side surfaces 2e and 2f.

The coil 5B includes a first coil portion 8B and a second coil portion 9B. The first coil portion 8B is constituted by the plurality of coil conductor layers 32b to 32f. The first coil portion 8B is disposed on a side of the main surface 2c of the element body 2. The first coil portion 8B has one end of the coil 5B connected to the first connection conductor 6. The first coil portion 8B is connected to the first connection conductor 6. The second coil portion 9B is constituted by the plurality of coil conductor layers 32g and 32h. The second coil portion 9B is disposed on a side of the main surface 2d of the element body 2. The second coil portion 9B has the other end of the coil 5B connected to the second connection conductor 7. The second coil portion 9B is connected to the second connection conductor 7.

FIG. 9 is an exploded perspective view of the multilayer coil component. As shown in FIG. 9, the multilayer coil component 1B includes a plurality of layers LBa, LBb, LBC, LBd, LBe, LBf, LBg, LBh, LBi, LBj, and LBk. The multilayer coil component 1B is constituted by the layers LBa to LBk being stacked in order from a side of the main surface 2c, for example.

The layer LBa is constituted by the element body layer 30a.

The layer LBb is formed by combining the element body layer **30b** and the coil conductor layer **32b** with each other. The element body layer **30b** is provided with a defective portion RBb. The layer LBc is formed by combining the element body layer **30c**, the coil conductor layer **32c**, and a first connection conductor layer **34c** with each other. The element body layer **30c** is provided with a defective portion RBc.

The layer LBd is formed by combining the element body layer **30d**, the coil conductor layer **32d**, and a first connection conductor layer **34d** with each other. The element body layer **30d** is provided with a defective portion RBd. The layer LBe is formed by combining the element body layer **30e**, the coil conductor layer **32e**, and a first connection conductor layer **34e** with each other. The element body layer **30e** is provided with a defective portion RBe.

The layer LBf is formed by combining the element body layer **30f**, the coil conductor layer **32f**, and a first connection conductor layer **34f** with each other. The element body layer **30f** is provided with a defective portion RBf. The layer LBg is formed by combining the element body layer **30g**, the coil conductor layer **32g**, and a first connection conductor layer **34g** with each other. The element body layer **30g** is provided with a defective portion RBg.

The layer LBh is formed by combining the element body layer **30h**, the coil conductor layer **32h**, and a first connection conductor layer **34h** with each other. The element body layer **30h** is provided with a defective portion RBh. The layer LBi is formed by combining the element body layer **30i**, a first connection conductor layer **34i**, and a second connection conductor layer **36i** with each other. The element body layer **30i** is provided with a defective portion RBi.

The layer LBj is formed by combining the element body layer **30j**, a first connection conductor layer **34j**, and a second connection conductor layer **36j** with each other. The element body layer **30j** is provided with a defective portion RBj. The layer LBk is formed by combining the element body layer **30k**, a first terminal electrode layer **38k**, and a second terminal electrode layer **39k** with each other. The element body layer **30k** is provided with a defective portion RBk.

As shown in FIG. 10, in the multilayer coil component 1B, a distance L2 between the first connection conductor **6** and the second coil portion **9B** is larger than a distance L1 between the first connection conductor **6** and the first coil portion **8B**. In other words, the distance L1 between the first connection conductor **6** and the first coil portion **8B** is smaller than the distance L2 between the first connection conductor **6** and the second coil portion **9B**. That is, the second coil portion **9B** is disposed farther from the first connection conductor **6** than the first coil portion **8B**. In the multilayer coil component 1B, in the coil conductor layer **32g** constituting the second coil portion **9B**, a portion facing the first connection conductor **6** is set as an oblique side. As a result, in the multilayer coil component 1B, the distance L2 between the first connection conductor **6** and the second coil portion **9B** is larger than the distance L1 between the first connection conductor **6** and the first coil portion **8B** (the coil conductor layers **32b** to **32f**). The distance L2 is the shortest distance between the first connection conductor **6** and the second coil portion **9B** (the coil conductor layers **32g** and **32h**). In FIG. 10, the distance L1 and the distance L2 are shown as an example for convenience and may differ from the actual shortest distance.

The diameter of the first coil portion **8B** and the diameter of the second coil portion **9B** are substantially equivalent to each other. A coil axis of the first coil portion **8B** and a coil axis of the second coil portion **9B** substantially coincide with each other. When viewed in the first direction D1, parts of the coil conductor layer **32b** and the coil conductor layer **32e** constituting the first coil portion **8B** and a part of the coil conductor layer **32h** constituting the second coil portion **9B** overlap each other.

As described above, in the multilayer coil component 1B according to the present embodiment, similarly to the multilayer coil component 1, the distance L2 between the first connection conductor **6** and the second coil portion **9B** is larger than the distance L1 between the first connection conductor **6** and the first coil portion **8B**. As a result, in the multilayer coil component 1B, the second coil portion **9B** with a large potential difference from the first connection conductor **6** is disposed farther from the first connection conductor **6** than the first coil portion **8B**. Therefore, in the multilayer coil component 1B, stray capacitance formed between the first connection conductor **6** and the second coil portion **9B** can be reduced. Further, in the multilayer coil component 1B, the diameter of the first coil portion **8B** can be increased. Therefore, the inductance of the coil **5B** can be increased. As described above, in the multilayer coil component 1B, it is possible to suppress the generation of stray capacitance and to increase the characteristics.

In the multilayer coil component 1B according to the present embodiment, in the coil conductor layer **32g** constituting the second coil portion **9B**, a portion facing the first connection conductor **6** is set as an oblique side. As a result, in the multilayer coil component 1B, the distance L2 between the first connection conductor **6** and the second coil portion **9B** is larger than the distance L1 between the first connection conductor **6** and the first coil portion **8B**. In this configuration, the diameter of the second coil portion **9B** can be increased. Therefore, in the multilayer coil component 1B, the characteristics can be improved.

Fourth Embodiment

Subsequently, a multilayer coil component according to a fourth embodiment will be described with reference to FIGS. 11 and 12. FIG. 11 is a perspective view of the multilayer coil component according to the fourth embodiment. FIG. 12 is a side view of the multilayer coil component shown in FIG. 11. As shown in FIGS. 11 and 12, a multilayer coil component 1C according to the fourth embodiment includes an element body **2**, a first terminal electrode **3**, a second terminal electrode **4**, a coil **5C**, a first connection conductor **6C**, and a second connection conductor **7C**. In FIGS. 11 and 12, the element body **2** is shown by a broken line for convenience of explanation.

The element body **2** is formed by stacking a plurality of element body layers **40a** to **40k** (see FIG. 13) in the first direction D1.

The coil **5C** is disposed in the element body **2**. The coil **5C** is constituted by a plurality of coil conductor layers **42b** to **42h** (see FIG. 13) and a plurality of through hole conductors **43a** to **43h**. The plurality of coil conductor layers **42b** to **42h** are connected to each other by the plurality of through hole conductors **43a** to **43h** to constitute the coil **5C** in the element body **2**. A coil axis of the coil **5C** is provided in the first direction D1. The coil conductor layers **42b** to **42h** are disposed such that at least parts thereof overlap each other when viewed in the first direction D1. The plurality of coil conductor layers **42b** to **42h** are made of a conductive

material (for example, Ag or Pd). The coil conductor layers 42b to 42h are disposed apart from the end surfaces 2a and 2b, the main surfaces 2c and 2d, and the side surfaces 2e and 2f.

The coil 5C includes a first coil portion 8C and a second coil portion 9C. The first coil portion 8C is constituted by the plurality of coil conductor layers 42b to 42d. The first coil portion 8C is disposed on a side of the main surface 2c of the element body 2. The first coil portion 8C has one end of the coil 5C connected to the first connection conductor 6C. The first coil portion 8C is connected to the first connection conductor 6C. The second coil portion 9C is constituted by the plurality of coil conductor layers 42e to 42h. The second coil portion 9C is disposed on a side of the main surface 2d of the element body 2. The second coil portion 9C has the other end of the coil 5C connected to the second connection conductor 7C. The second coil portion 9C is connected to the second connection conductor 7C.

The first connection conductor 6C is disposed in the element body 2. The first connection conductor 6C connects the first terminal electrode 3 and the coil 5C to each other. The first connection conductor 6C is a through hole conductor. The first connection conductor 6C is constituted by a plurality of first through hole conductor layers 44c to 44j (see FIG. 13).

The second connection conductor 7C is disposed in the element body 2. The second connection conductor 7C connects the second terminal electrode 4 and the coil 5C to each other. The second connection conductor 7C is a through hole conductor. The second connection conductor 7C is constituted by a plurality of second through hole conductor layers 46i and 46j (see FIG. 13).

FIG. 13 is an exploded perspective view of the multilayer coil component. As shown in FIG. 13, the multilayer coil component 1C includes a plurality of layers LCa, LCb, LCC, LCD, LCE, LCf, LCg, LCh, LCi, LCj, and LCk. The multilayer coil component 1C is constituted by the layers LCa to LCk being stacked in order from a side of the main surface 2c, for example.

The layer LCa is constituted by the element body layer 40a.

The layer LCb is formed by providing the coil conductor layer 42b on the element body layer 40b. The layer LCC is formed by providing the coil conductor layer 42c on the element body layer 40c and by being provided with the first through hole conductor layer 44c. The coil conductor layer 42b and the first through hole conductor layer 44c are connected to each other by the through hole conductor 43a. The coil conductor layer 42b and the coil conductor layer 42c are connected to each other by the through hole conductor 43b.

The layer LCD is formed by providing the coil conductor layer 42d on the element body layer 40d and by being provided with the first through hole conductor layer 44d. The coil conductor layer 42c and the coil conductor layer 42d are connected to each other by the through hole conductor 43c.

The layer LCE is formed by providing the coil conductor layer 42e on the element body layer 40e and by being provided with the first through hole conductor layer 44e. The coil conductor layer 42d and the coil conductor layer 42e are connected to each other by the through hole conductor 43d.

The layer LCf is formed by providing the coil conductor layer 42f on the element body layer 40f and by being provided with the first through hole conductor layer 44f. The coil conductor layer 42e and the coil conductor layer 42f are connected to each other by the through hole conductor 43e.

The layer LCg is formed by providing the coil conductor layer 42g on the element body layer 40g and by being provided with the first through hole conductor layer 44g. The coil conductor layer 42f and the coil conductor layer 42g are connected to each other by the through hole conductor 43f.

The layer LCh is formed by providing the coil conductor layer 42h on the element body layer 40h and by being provided with the first through hole conductor layer 44h. The coil conductor layer 42g and the coil conductor layer 42h are connected to each other by the through hole conductor 43g.

The layer LCi is formed by providing the first through hole conductor layer 44i and the second through hole conductor layer 46i in the element body layer 40i. The coil conductor layer 42h and the second through hole conductor layer 46i are connected to each other by the through hole conductor 43h.

The layer LCj is formed by providing the first through hole conductor layer 44j and the second through hole conductor layer 46j in the element body layer 40j. The layer LCk is formed by providing the first terminal electrode 3 and the second terminal electrode 4 in the element body layer 40k.

As shown in FIG. 12, in the multilayer coil component 1C, a distance L2 between the first connection conductor 6C and the second coil portion 9C is larger than a distance L1 between the first connection conductor 6C and the first coil portion 8C. In other words, the distance L1 between the first connection conductor 6C and the first coil portion 8C is smaller than the distance L2 between the first connection conductor 6C and the second coil portion 9C. That is, the second coil portion 9C is disposed farther from the first connection conductor 6C than the first coil portion 8C. The distance L1 is the shortest distance between the first connection conductor 6C and the first coil portion 8C (the coil conductor layers 42b to 42d). The distance L2 is the shortest distance between the first connection conductor 6C and the second coil portion 9C (the coil conductor layers 42e to 42h). In FIG. 12, the distance L1 and the distance L2 are shown as an example for convenience and may differ from the actual shortest distance.

A diameter of the first coil portion 8C and a diameter of the second coil portion 9C are different. The diameter of the first coil portion 8C is larger than the diameter of the second coil portion 9C. In other words, the diameter of the second coil portion 9C is smaller than the diameter of the first coil portion 8C. A coil axis of the first coil portion 8C and a coil axis of the second coil portion 9C do not coincide with each other. The coil axis of the second coil portion 9C is located closer to the end surface 2b than the coil axis of the first coil portion 8C. An edge of the first coil portion 8C and an edge of the second coil portion 9C on a side of the end surface 2b of the element body 2 coincide with each other in the first direction D1. Specifically, when viewed in the first direction D1, parts of the coil conductor layer 42b and coil conductor layer 42d constituting the first coil portion 8C and parts of the coil conductor layer 42f and the coil conductor layer 42h constituting the second coil portion 9C overlap each other.

The second coil portion 9C does not overlap the first terminal electrode 3 when viewed in the first direction D1. That is, the second coil portion 9C is not located above the first terminal electrode 3. Specifically, the coil conductor layers 42e to 42h do not overlap the first terminal electrode 3 when viewed in the first direction D1.

Subsequently, a method of manufacturing the multilayer coil component 1C will be described.

Slurry is prepared by mixing an insulating resin and a solvent. The prepared slurry is applied onto a base material (for example, a PET film) by a doctor blade method to form green sheets to be the element body layers 40a to 40k. Next, through holes are formed by laser processing at planned formation positions of the through hole conductors 43a to 43h, the first through hole conductor layers 44b to 44j, and the second through hole conductor layers 46i and 46j in the green sheets.

Subsequently, the through holes of the green sheets are filled with a first conductive paste. The first conductive paste is produced by mixing conductive metal powder, a binder resin, and the like. Subsequently, conductors to be the coil conductor layers 42b to 42h are provided on the green sheet. At this time, the conductors are connected to the conductive pastes in the through holes.

Subsequently, the green sheets are stacked. Here, a plurality of green sheets provided with the conductors are detached from the base material and stacked, and pressure is applied in the stacking direction to form a multilayer body. At this time, the green sheets are stacked such that the conductors to be the coil conductor layers 42b to 42h overlap each other in the stacking direction.

Subsequently, the multilayer body of the green sheets is cut into a chip of a predetermined size with a cutting machine to obtain a green chip. Subsequently, after the binder resin contained in each portion is removed from the green chip, the green chip is fired. As a result, the element body 2 is obtained.

Subsequently, a second conductive paste is provided on the main surface 2d of the element body 2. The second conductive paste is produced by mixing conductive metal powder, glass frit, a binder resin, and the like. Subsequently, the second conductive paste is baked in the element body 2 by heat treatment to form the first terminal electrode 3 and the second terminal electrode 4. If necessary, the first terminal electrode 3 and the second terminal electrode 4 may be provided with a plated layer by being subjected to electroplating or electroless plating. By the above steps, the multilayer coil component 1C is obtained.

As described above, in the multilayer coil component 1C according to the present embodiment, similarly to the multilayer coil component 1, the distance L2 between the first connection conductor 6C and the second coil portion 9C is larger than the distance L1 between the first connection conductor 6C and the first coil portion 8C. As a result, in the multilayer coil component 1C, the second coil portion 9C with a large potential difference from the first connection conductor 6C is disposed farther from the first connection conductor 6C than the first coil portion 8C. Therefore, in the multilayer coil component 1C, stray capacitance formed between the first connection conductor 6C and the second coil portion 9C can be reduced. Further, in the multilayer coil component 1C, the diameter of the first coil portion 8C can be increased. Therefore, the inductance of the coil 5C can be increased. As described above, in the multilayer coil component 1C, it is possible to suppress the generation of stray capacitance and to increase the characteristics.

Fifth Embodiment

Subsequently, a multilayer coil component according to a fifth embodiment will be described with reference to FIGS. 14 and 15. FIG. 14 is a perspective view of the multilayer coil component according to the fifth embodiment. FIG. 15 is a side view of the multilayer coil component shown in FIG. 14. As shown in FIGS. 14 and 15, a multilayer coil

component 1D according to the fifth embodiment includes an element body 2, a first terminal electrode 3, a second terminal electrode 4, a coil 5D, a first connection conductor 6D, and a second connection conductor 7D. In FIGS. 14 and 15, the element body 2 is shown by a broken line for convenience of explanation.

The element body 2 is formed by stacking a plurality of element body layers 50a to 50k (see FIG. 16) in the first direction D1.

The coil 5D is disposed in the element body 2. The coil 5D is constituted by a plurality of coil conductor layers 52b to 52h (see FIG. 16) and a plurality of through hole conductors 53a to 53h. The plurality of coil conductor layers 52b to 52h are connected to each other by the plurality of through hole conductors 53a to 53h to constitute the coil 5D in the element body 2. A coil axis of the coil 5D is provided in the first direction D1. The coil conductor layers 52b to 52h are disposed such that at least parts thereof overlap each other when viewed in the first direction D1. The plurality of coil conductor layers 52b to 52h are made of a conductive material (for example, Ag or Pd). The coil conductor layers 52b to 52h are disposed apart from the end surfaces 2a and 2b, the main surfaces 2c and 2d, and the side surfaces 2e and 2f.

The coil 5D includes a first coil portion 8D, a second coil portion 9D, and a third coil portion 10D. The first coil portion 8D is constituted by the plurality of coil conductor layers 52b to 52d. The first coil portion 8D is disposed on a side of the main surface 2c of the element body 2. The first coil portion 8D has one end of the coil 5D connected to the first connection conductor 6D. The first coil portion 8D is connected to the first connection conductor 6D. The second coil portion 9D is constituted by the plurality of coil conductor layers 52g and 52h. The second coil portion 9D is disposed on a side of the main surface 2d of the element body 2. The second coil portion 9D has the other end of the coil 5D connected to the second connection conductor 7D. The second coil portion 9D is connected to the second connection conductor 7D. The third coil portion 10D is constituted by the plurality of coil conductor layers 52e and 52f. The third coil portion 10D is disposed between the first coil portion 8D and the second coil portion 9D. One end of the third coil portion 10D is connected to the first coil portion 8D, and the other end of the third coil portion 10D is connected to the second coil portion 9D.

The first connection conductor 6D is disposed in the element body 2. The first connection conductor 6D connects the first terminal electrode 3 and the coil 5D to each other. The first connection conductor 6D is a through hole conductor. The first connection conductor 6D is constituted by a plurality of first through hole conductor layers 54c to 54j (see FIG. 16).

The second connection conductor 7D is disposed in the element body 2. The second connection conductor 7D connects the second terminal electrode 4 and the coil 5D to each other. The second connection conductor 7D is a through hole conductor. The second connection conductor 7D is constituted by a plurality of second through hole conductor layers 56i and 56j (see FIG. 16).

FIG. 16 is an exploded perspective view of the multilayer coil component. As shown in FIG. 16, the multilayer coil component 1D includes a plurality of layers LDa, LD_b, LD_c, LD_d, LD_e, LD_f, LD_g, LD_h, LD_i, LD_j, and LD_k. The multilayer coil component 1D is constituted by the layers LDa to LD_k being stacked in order from a side of the main surface 2c, for example.

21

The layer LD_a is constituted by the element body layer 50a.

The layer LD_b is formed by providing the coil conductor layer 52b on the element body layer 50b. The layer LD_c is formed by providing the coil conductor layer 52c on the element body layer 50c and by being provided with the first through hole conductor layer 54c. The coil conductor layer 52b and the first through hole conductor layer 54c are connected to each other by the through hole conductor 53a. The coil conductor layer 52b and the coil conductor layer 52c are connected to each other by the through hole conductor 53b.

The layer LD_d is formed by providing the coil conductor layer 52d on the element body layer 50d and by being provided with the first through hole conductor layer 54d. The coil conductor layer 52c and the coil conductor layer 52d are connected to each other by the through hole conductor 53c.

The layer LD_e is formed by providing the coil conductor layer 52e on the element body layer 50e and by being provided with the first through hole conductor layer 54e. The coil conductor layer 52d and the coil conductor layer 52e are connected to each other by the through hole conductor 53d.

The layer LD_f is formed by providing the coil conductor layer 52f on the element body layer 50f and by being provided with the first through hole conductor layer 54f. The coil conductor layer 52e and the coil conductor layer 52f are connected to each other by the through hole conductor 53e.

The layer LD_g is formed by providing the coil conductor layer 52g on the element body layer 50g and by being provided with the first through hole conductor layer 54g. The coil conductor layer 52f and the coil conductor layer 52g are connected to each other by the through hole conductor 53f.

The layer LD_h is formed by providing the coil conductor layer 52h on the element body layer 50h and by being provided with the first through hole conductor layer 54h. The coil conductor layer 52g and the coil conductor layer 52h are connected to each other by the through hole conductor 53g.

The layer LD_i is formed by providing the first through hole conductor layer 54i and the second through hole conductor layer 56i in the element body layer 50i. The coil conductor layer 52h and the second through hole conductor layer 56i are connected to each other by the through hole conductor 53h.

The layer LD_j is formed by providing the first through hole conductor layer 54j and the second through hole conductor layer 56j in the element body layer 50j. The layer LD_k is formed by providing the first terminal electrode 3 and the second terminal electrode 4 in the element body layer 50k.

As shown in FIG. 15, in the multilayer coil component 1D, a distance L₂ between the first connection conductor 6D and the second coil portion 9D is larger than a distance L₁ between the first connection conductor 6D and the first coil portion 8D. In other words, the distance L₁ between the first connection conductor 6D and the first coil portion 8D is smaller than the distance L₂ between the first connection conductor 6D and the second coil portion 9D. That is, the second coil portion 9D is disposed farther from the first connection conductor 6D than the first coil portion 8D. Further, a distance L₃ between the first connection conductor 6D and the third coil portion 10D is larger than the distance L₁ between the first connection conductor 6D and

22

the first coil portion 8D and smaller than the distance L₂ between the first connection conductor 6D and the second coil portion 9D (L₁>L₃>L₂).

In the multilayer coil component 1D, the distances L₁, L₂, and L₃ between the first connection conductor 6D and the first, second, and third coil portions 8D, 9D, and 10D are set on the basis of a potential difference generated when the multilayer coil component 1D is used. Specifically, in the multilayer coil component 1D, the distances L₁, L₂, and L₃ between the first connection conductor 6D and the first, second, and third coil portions 8D, 9D, and 10D are set such that the larger a potential difference between the coil portion and the first connection conductor 6D, the larger a distance between the coil portion and the first connection conductor 6D. The potential difference is the largest between the first connection conductor 6D and the second coil portion 9D and is the smallest between the first connection conductor 6D and the first coil portion 8D. The potential difference becomes larger in the order of the potential difference between the first connection conductor 6D and the first coil portion 8D, the potential difference between the first connection conductor 6D and the third coil portion 10D, and the potential difference between the first connection conductor 6D and the second coil portion 9D. As a result, in the multilayer coil component 1D, the distance between the first connection conductor 6D and the coil portion becomes larger in the order of the distance L₁ between the first connection conductor 6D and the first coil portion 8D, the distance L₃ between the first connection conductor 6D and the third coil portion 10D, and the distance L₂ between the first connection conductor 6D and the second coil portion 9D.

The distance L₁ is the shortest distance between the first connection conductor 6D and the first coil portion 8D (the coil conductor layers 52b to 52d). The distance L₂ is the shortest distance between the first connection conductor 6D and the second coil portion 9D (the coil conductor layers 52g and 52h). The distance L₃ is the shortest distance between the first connection conductor 6D and the third coil portion 10D (the coil conductor layers 52e and 52f). In FIG. 15, the distance L₁, the distance L₂, and the distance L₃ are shown as an example for convenience and may differ from the actual shortest distance.

A diameter of the first coil portion 8D, a diameter of the second coil portion 9D, and a diameter of the third coil portion 10D are different. The diameter of the first coil portion 8D is larger than each of the diameter of the second coil portion 9D and the diameter of the third coil portion 10D. The diameter of the third coil portion 10D is larger than the diameter of the second coil portion 9D. A coil axis of the first coil portion 8D, a coil axis of the second coil portion 9D, and a coil axis of the third coil portion 10D do not coincide with each other. The coil axis of the second coil portion 9D is located closer to the end surface 2b than the coil axis of the first coil portion 8D and the coil axis of the third coil portion 10D. The coil axis of the third coil portion 10D is located closer to the end surface 2b than the coil axis of the first coil portion 8D.

An edge of the first coil portion 8D, an edge of the second coil portion 9D, and an edge of the third coil portion 10D on a side of the end surface 2b of the element body 2 coincide with each other in the first direction D₁. Specifically, when viewed in the first direction D₁, parts of the coil conductor layer 52b and coil conductor layer 52d constituting the first coil portion 8D, a part of the coil conductor layer 52h

constituting the second coil portion 9D, and a part of the coil conductor layer 52f constituting the third coil portion 10D overlap each other.

The second coil portion 9D and the third coil portion 10D do not overlap the first terminal electrode 3 when viewed in the first direction D1. That is, the second coil portion 9D and the third coil portion 10D are not located above the first terminal electrode 3. Specifically, the coil conductor layers 52e to 52h do not overlap the first terminal electrode 3 when viewed in the first direction D1.

As described above, in the multilayer coil component 1D according to the present embodiment, similarly to the multilayer coil component 1, the distance L2 between the first connection conductor 6D and the second coil portion 9D is larger than each of the distance L1 between the first connection conductor 6D and the first coil portion 8D and the distance L3 between the first connection conductor 6D and the third coil portion 10D. As a result, in the multilayer coil component 1D, the second coil portion 9D and the third coil portion 10D with a large potential difference from the first connection conductor 6D are disposed farther from the first connection conductor 6D than the first coil portion 8D. Therefore, in the multilayer coil component 1D, stray capacitance formed between the first connection conductor 6D and the second coil portion 9D can be reduced. Further, in the multilayer coil component 1D, the diameter of the first coil portion 8D can be increased. Therefore, the inductance of the coil 5D can be increased. As described above, in the multilayer coil component 1D, it is possible to suppress the generation of stray capacitance and to increase the characteristics.

In the multilayer coil component 1D according to the present embodiment, the distances L1, L2, and L3 between the first connection conductor 6D and the first, second, and third coil portions 8D, 9D, and 10D are set on the basis of a potential difference generated when the multilayer coil component 1D is used. Specifically, in the multilayer coil component 1D, the distances L1, L2, and L3 between the first connection conductor 6D and the first, second, and third coil portions 8D, 9D, and 10D are set such that the larger a potential difference between the coil portion and the first connection conductor 6D, the larger a distance between the coil portion and the first connection conductor 6D. In this configuration, since the distance is set according to the potential difference, the stray capacitance can be reduced.

Although the embodiments of the present invention have been described above, the present invention is not necessarily limited to the above described embodiments, and various modifications can be made without departing from the gist thereof.

In the above embodiments, a configuration in which each of the first terminal electrode 3 and the second terminal electrode 4 has a rectangular shape has been described as an example. However, the shape of each of the first terminal electrode 3 and the second terminal electrode 4 is not limited to this.

In the above embodiments, a configuration in which the first connection conductor 6, 6C, 6D and the second connection conductor 7, 7C, 7D are disposed at diagonal positions has been described as an example. However, the first connection conductor 6, 6C, 6D and the second connection conductor 7, 7C, 7D may be disposed at other positions.

In the above embodiment, a configuration in which each of the first connection conductor 6, 6C, 6D and the second connection conductor 7, 7C, 7D has a shape of a circular column have been described as an example. However, the

shape of each of the first connection conductor 6, 6C, 6D and the second connection conductor 7, 7C, 7D is not limited to this and may be a triangular column, a prismatic column, or the like.

In the above embodiment, a configuration in which the coil 5 is constituted by a plurality of coil conductor layers 12b to 12h, the first coil portion 8 is constituted by the coil conductor layers 12b to 12d, and the second coil portion 9 is constituted by the coil conductor layers 12e to 12h has been described as an example. However, the number of coil conductor layers constituting the coil 5 is not limited to the above-mentioned value. Further, the number of coil conductor layers constituting the first coil portion 8 and the number of coil conductor layers constituting the second coil portion 9 may be the same or different. Further, the coil 5 may include another coil portion. The same applies to the coil 5A, 5B, 5C, 5D.

What is claimed is:

1. A multilayer coil component comprising:
an element body formed by stacking a plurality of insulator layers and having a pair of end surfaces facing each other, a pair of main surfaces facing each other, and a pair of side surfaces facing each other, one of the main surfaces being a mounting surface;
a coil disposed in the element body and having a coil axis extending in a facing direction of the pair of main surfaces;
a first terminal electrode and a second terminal electrode connected to the coil and disposed on the mounting surface;
a first connection conductor disposed outside the coil in the element body when viewed in the facing direction, extending in the facing direction, and connecting one end of the coil located on a side of the other of the main surfaces and the first terminal electrode to each other; and
a second connection conductor connecting the other end of the coil located on a side of the one of the main surfaces and the second terminal electrode,
wherein the coil comprises a first coil portion and a second coil portion, each of the first coil portion and the second coil portion being formed on two or more of the plurality of the insulator layers, the first coil portion having the one end of the coil and being disposed on a side of the other of the main surfaces, the second coil portion having the other end of the coil and being disposed on a side of the one of the main surfaces, and
wherein a shortest distance between the first connection conductor and the second coil portion is larger than a shortest distance between the first connection conductor and the first coil portion.

2. The multilayer coil component according to claim 1, wherein a diameter of the first coil portion and a diameter of the second coil portion are different, and
wherein a part of an outer edge of the first coil portion and a part of an outer edge of the second coil portion overlap each other when viewed in the facing direction.

3. The multilayer coil component according to claim 1, wherein the first terminal electrode and the second coil portion do not overlap each other when viewed in the facing direction.

4. The multilayer coil component according to claim 1, wherein a distance between the first connection conductor and the coil is set on the basis of a potential difference between the first connection conductor and the coil during use, and

wherein the distance is longer at a position where the potential difference is large than at a position where the potential difference is smaller than at the position where the potential difference is large.
